SAND PUMP BOTTOM

George W. Miller, Sapulpa, Okla.

Application July 18, 1938, Serial No. 219,705

5 Claims. (Cl. 166—19)

This invention relates to sand pumps and more particularly to the structure of the bottom thereof by which sandy material and like debris in oil or similar wells are loosened, collected and trapped in the barrel of the pump for removing the debris from the well in cleaning-out operations. The principal objects of the present invention are to provide an improved bottom structure for sand pumps; to provide an improved debris trapping mechanism for the sand pump; to provide for latching the trapping mechanism whereby debris may enter the pump barrel and be retained therein until it is desired to remove the same from the barrel; to provide an improved debris loosening mechanism capable of employment in connection with the sand pump and trapping mechanism; to provide improved parts and arrangements of those parts in the construction of a sand pump of this character; and to provide a relatively inexpensive, highly efficient, and very durable sand pump embodying the features of this invention.

In accomplishing these and other objects of the present invention, I have provided improved details of structure, the preferred forms of which are illustrated in the accompanying drawings, wherein:

Fig. 1 is a perspective view of the lower end of a sand pump barrel illustrating the preferred form of my improved sand pump bottom structure applied thereto.

Fig. 2 is a vertical cross-section through the lower end of the sand pump on the line 2—2, Fig. 1, illustrating the trap valve mechanism in debris-admitting condition.

Fig. 3 is a similar vertical cross-section through the lower end of the sand pump, the trap valve mechanism being illustrated in debris-releasing condition.

Fig. 4 is a horizontal cross-section through the lower end of the sand pump substantially on the line 4—4, Fig. 2, illustrating the trap and valve mechanism in closed condition.

Fig. 5 is a detail perspective view of a sand pump bottom structure embodying this invention, illustrating the manner of releasing the trap valve latching mechanism.

Fig. 6 is a detail perspective view of a sand pump bottom structure illustrating a modified form of trap valve mechanism latch.

Fig. 7 is a vertical cross-section through the modified form of sand pump bottom structure illustrated in Fig. 6, showing the latching mechanism in trap valve closing condition.

Fig. 8 is a horizontal cross-section through the

modified form of sand pump bottom structure substantially on the line 8—8, Fig. 7.

Fig. 9 is a perspective view of a sand pump bottom structure embodying the features of the present invention illustrating a debris loosening mechanism applied thereto, the debris loosening mechanism being shown in contracted bottom structure engaging condition.

Fig. 10 is a perspective view similar to Fig. 9 illustrating the debris loosening mechanism in protracted condition.

Fig. 11 is a detail vertical cross-section of the debris loosening mechanism on the line 11—11, Fig. 9.

Fig. 12 is a horizontal cross-section through the debris loosening mechanism on the line 12—12, Fig. 11.

Referring more in detail to the drawings:

The apparatus embodying the preferred form of the present invention preferably includes a sand pump barrel 1, the lower end of which has sleeved therein or otherwise secured thereto, as by rivets or the like 2, a bushing 3. The bushing 3 is preferably internally threaded at its lower end for receiving the sand pump bottom structure embodying the principal features of the present invention.

The bottom structure 4 is of preferably generally cylindrical or tubular conformation and has threaded engagement with the bushing 3 at its upper reduced end 5. The reduced end 5 of the bottom structure is provided with a shoulder 6 for engagement with the lower end of the bushing. The hollow interior of the bottom structure is provided, substantially midway the length thereof, with the trap valve mechanism 7, now to be described.

8 designates a recess in the inner wall of the bottom structure for receiving the pivoted end 9 of the trap valve mechanism on a pin 10 suitably mounted on the bottom structure in transverse relation thereto, as particularly illustrated at 11 in Fig. 4. The trap valve mechanism preferably consists of an annular ring 12 extendible laterally of the pivoted end thereof and engageable at its upper face portion with an inwardly extending annular shoulder 13 on the inner wall of the bottom structure 4. A valve 14 having a tapered seat 15, seats on the ring to close the opening 16 therein and the valve 14 is pivoted on the ring 12 by extension of a pin 17 through ears 18 on the valve and a lug 19 extending upwardly from the ring adjacent the pivoted end 9.

In order to retain the trap valve mechanism in closed condition, as illustrated in Fig. 4, the

latch mechanism 20 is provided, which preferably consists of an arm 21 pivotally mounted at its lower end on a pivot pin 22 suitably mounted in the bottom structure of the sand pump and 5 transversely thereof, as particularly illustrated in dotted lines at 23 in Fig. 4.

The upper end 24 of the arm 21 is provided with an inner face engageable within a recess 25 in the bottom structure in such a manner that 10 the outer face of the latching arm 21 is substantially flush with the outer surface of the pump in order to avoid protuberances which might impede the proper unhindered reciprocation of the sand pump in a well.

15 The recess 25 is offset inwardly substantially at its upper end, as at 26, to form a seat for a lug 27 on the arm 21 to effect substantial locking engagement of the arm 21 with the bottom structure wall. An inwardly extending boss 28 is also 20 provided on the upper end of the arm 21 below the lug 27 and end 24 thereof, the boss 28 being of a size sufficient to form a seat 29 for the ring 12 of the trap valve mechanism, as particularly illustrated in Fig. 2.

25 In order to normally maintain engagement between the trap valve mechanism and latching mechanism, a spring 30 is preferably employed, the lower end of which spring is fixed to the bottom structure at the lower end of the recess 25, 30 as by rivets 31 or similar fastening devices. The upper end of the spring bears against the outer face of the latching arm 21 for normally urging the latching arm inwardly, as shown in Fig. 2, the arrangement of the spring being such that 35 the pump barrel, the bushing, the bottom structure, and the latching mechanism lie in substantially the same circular plane, thereby avoiding the possibility of unintentionally unlatching the trap valve mechanism prematurely when the 40 pump barrel is withdrawn from the well.

The lower end of the bottom structure is provided with suitable cut outs 32, the bounding surfaces of which form bit or like points for engaging sand or other debris in a well and loosening 45 same to prepare the debris for admission into the hollow interior of the pump barrel.

The operation of a sand pump embodying the features of my preferred form of invention is as follows:

50 Assuming the pump to be in the condition illustrated in Fig. 3, that is, with the load removed therefrom, and further assuming that the sand pump is at the top of the well; the ring 12 may be manually engaged and forced upwardly into 55 engagement with the bottom tapered edge of the boss 28 of the latching arm 21 for moving the latching arm outwardly against tension of the spring to permit extension of the ring 12 into engagement with the lower face of the annular 60 ring 13 of the bottom structure. In this position of the ring 12, the spring 30 is permitted to come into play to force the latching arm 21 inwardly in such a manner that the boss 28 thereof forms a supporting seat for the ring 12 of the trap valve 65 mechanism.

The sand pump is then lowered to the bottom of a well and the bounding edges of the cutouts 32 loosen debris in the well. Suitable plunger mechanism, not shown, is then actuated for creating a suction within the barrel to unseat the valve 14 and admit debris into the pump barrel. When the pump barrel is full, the sand pump may be removed from the well, upward movement thereof causing downward movement of the valve 70 14 to close off the lower end of the sand pump

barrel, thereby retaining the debris in the barrel. The sand pump is then removed from the well and a suitable tool may be engaged with the upper end 24 of the latch arm as illustrated in Fig. 5 to force the latch arm outwardly against 5 tension of the spring 30. The seat for the ring 12 being removed, the trap valve mechanism pivots downwardly on the pin 10, as shown in Fig. 3, and the contents of the barrel are discharged. The described operation is then repeated until 10 the well is cleaned of debris.

In Figs. 6 to 8 inclusive, a sand pump bottom structure embodying features of my invention is illustrated, wherein a bushing 35, similar to the bushing 3 previously described, is suitably mounted in a sand pump barrel, not shown, and wherein a bottom structure 36 is provided with debris-engaging surfaces 38 which bound the cutouts 39, much in the same manner as the corresponding parts previously described. The trap valve 20 mechanism 40 is also substantially similar to that previously described and preferably includes a pivoted ring 41 having an opening 42 therein closed by a valve 43 pivotally mounted as at 44 on the ring 41.

25 The latching mechanism 45 in this form of the invention preferably consists of an arcuate insert 46, Fig. 6, mounted in an arcuate recess 47 extending transversely through the wall of the bottom structure. The insert 46 is pivotally mounted in the recess 47 by the pivot pin 48, Fig. 8, and has an ear 49 opposite its pivoted end which engages a tapered seat 50 upon the bottom structure wall to position the outer face of the insert 30 in flush relation with the outer surface of the 35 bottom structure wall.

The upper inner edge 51 of the insert is preferably tapered and forms a seat 52 for the ring 41 when the ring is raised and the insert is pivoted inwardly as illustrated in Fig. 7.

40 In order to retain the insert in ring-seating condition, a recess 53 is provided in the wall of the bottom structure above the recess 49, the lower bounding wall of which recess is provided with an aperture extending through the bottom 45 structure wall in alignment with a socket 54 adjacent one end of the insert 46. A pin 55 is mounted in the recess 53 and extends through the aperture therein for lodgment in the socket 54. A spring 56 is provided on the pin 55 and 50 seats at its lower end on a washer fixed to the pin. The upper end of the spring bears against the upper wall 57 of the recess in the bottom structure wall and about a socket 58 therein which receives the upper end of the pin 55. The 55 end of the pin below the washer is of a length adapting it for extension into the socket 54 of the insert to lock the insert in inwardly pivoted condition to seat the ring 41.

The operation of the modified form of latching 60 mechanism employed in connection with this form of the invention is as follows:

65 Assuming the sand pump to have been emptied at the top of the well and to be in the condition illustrated in Fig. 6, the ring 41 is moved upwardly on its pivot and the insert 46 is moved inwardly on its pivot 48 to underlie and seat the ring 41. The pin 55 is moved upwardly upon engagement of the beveled inner edge 51 of the insert therewith to permit inward pivotal movement of the insert and the spring 56 causes 70 downward movement of the pin into the socket 54 when the pin overlies the socket to latch the insert in ring-seating condition. The sand pump is then lowered in the well, and the ends 38 of 75

the bottom structure loosen debris in the well, which debris is drawn into the interior 59 of the bottom structure in the usual manner and when the pump barrel is full, it is then drawn 5 out of the well. Upward movement of the sand pump causes the valve 43 to seat on the ring 41 to close the opening 42 therein to trap the debris in the pump barrel.

When the sand pump has reached the top of 10 the well, a suitable tool, not shown, may be applied between the lower wall of the recess 53 and the washer on the pin 55 for lifting the pin out of the socket 54 in such a manner that the insert may be pivoted outwardly to remove the 15 insert from ring-seating condition, at which time, the ring and valve drop downwardly on the ring pivot and the debris in the pump barrel is discharged.

The operation just described is then repeated 20 until the well is cleaned of debris.

In Figs. 9 to 12, a further modified form of invention is shown, wherein the bottom structure 65 is substantially similar to that illustrated in the preferred form of invention, and which includes a latching mechanism 66 adapted to latch a trap valve mechanism in the bottom structure in closed condition, as has already been described.

In this form of the invention, the lower debris loosening end 67 of the bottom structure is provided with a cross-member, as indicated at 68, which is provided with a vertically disposed bore 69 having an annular shoulder 70, Fig. 11, substantially at its lower end.

71 designates a bit and 72 represents a shank 35 extending upwardly from the bit, the shank having a head 73 thereon of substantially the same diameter as the bore 69. The head 73, however, is adapted to seat on the shoulder 70 at the lower end of the bore 69 for retaining the bit and bottom structure in interengaged relation.

In order to facilitate loosening of debris in a well hole, it is desirable to cause rotative movement of the bit in the hole and to this end, the bit is provided on its shank with a plurality of 45 threads 74 adapted to run in grooves 75 cut into the bore 69 of the cross-member 68. It has been found that a quarter turn of the bit 71 is satisfactory, and the threads and grooves are arranged in such a manner that when the sand 50 pump is in a position in the well, other than on the bottom of the well, gravity, acting on the bit effects extension of the bit to the lower end of the bore 69, as shown in Fig. 10, and engagement of the bit with the bottom of the well causes 55 retraction of the bit into the bottom structure, as shown in Fig. 9, the bit being given a quarter turn simultaneously with retraction thereof into engagement with the bottom structure.

In this manner, debris is loosened upon reciprocation of the sand pump in an oil or similar well and upon actuation of a plunger mechanism, not shown, the loosened debris may be drawn and passed through cut outs 76 in the sides of the bottom structure for passage through a suit-

able trap valve mechanism, preferably of the form illustrated in the other forms of the invention, and thence to the pump barrel supporting the sand pump bottom structure herein described for removal of the debris from the well in the 5 manner previously described.

If desired, suitable retaining devices, such as a screw 77, may be extended through the bottom structure into engagement with the shank 72 to lock the bit against rotation relative to the sand 10 pump bottom structure.

What I claim and desire to secure by Letters Patent is:

1. In a sand pump, a barrel, and a bottom structure for the pump mounted in said barrel, 15 said bottom structure including a tubular member extending downwardly from the barrel, a ring pivotally mounted in the tubular member, a valve pivotally mounted on said ring adapted to seat on said ring and close the opening therein, and a member pivotally mounted on said tubular member adapted to seat said ring for retaining the valve in barrel closing condition.

2. In a sand pump, a barrel, and a bottom structure for the pump mounted in said barrel, 25 said bottom structure including a tubular member extending downwardly from the barrel, a ring pivotally mounted in the tubular member, a valve pivotally mounted on said ring adapted to seat on said ring and close the opening therein, an 30 arm pivotally mounted on said tubular member having a boss adapted to seat said ring for retaining the valve in barrel closing condition, and means resiliently maintaining said arm in ring seating condition.

3. An apparatus of the character described including a tubular member, a valve mechanism pivotally mounted in said tubular member adapted to seat therein and close off the same, an insert pivotally mounted on the tubular member and engageable with said valve mechanism for retaining said mechanism in closed condition, and latching means mounted in said tubular member engageable with said insert.

4. An apparatus of the character described 45 including a tubular member, a ring pivotally mounted in said tubular member, a valve pivotally mounted on said ring adapted to seat thereon and close the opening therein, an insert pivotally mounted on the tubular member and engageable 50 with said ring for retaining the valve in closed condition, and latching means mounted in said tubular member engageable with said insert.

5. In a sand pump, a barrel, and a bottom structure for the pump mounted in said barrel, 55 said bottom structure including a tubular member projecting from the barrel, a valve mechanism mounted in said tubular member and adapted to seat therein and close off the same, and a member pivotally mounted on said tubular member and engageable with said valve mechanism to normally retain the same in barrel closing condition.

GEORGE W. MILLER.
